UNITED STATES PATENT OFFICE.

GEORGE W. LAKE, OF RUMFORD, RHODE ISLAND, ASSIGNOR OF ONE-HALF TO HARRIS W. PEARSON, OF PROVIDENCE, RHODE ISLAND.

DEVICE FOR WITHDRAWING LIQUID FROM CONTAINERS.

1,280,767.

Specification of Letters Patent.

Patented Oct. 8, 1918.

Application filed October 17, 1917. Serial No. 197,165.

To all whom it may concern:

Be it known that I, GEORGE W. LAKE, a citizen of the United States, and resident of the town of Rumford, in the county of Providence and State of Rhode Island, have invented certain new and useful Improvements in Devices for Withdrawing Liquid from Containers, of which the following is a specification.

10 This invention relates to devices for withdrawing liquid from a container by a siphonic action, the same being more particularly adapted for use in drawing off the top of milk from a bottle, one leg of which 15 is adapted to extend into the bottle and to provide simple and effective means for starting the flow of the liquid contents outward through the tube.

20 A further object of this invention is to provide simple and effective means whereby the U-tube may be adjusted vertically so as to regulate the depth to which the inwardly extending leg shall project into the bottle to control the amount which shall be drawn 25 therefrom.

With these and other objects in view, the invention consists of certain novel features of construction, as will be more fully described, and particularly pointed out in the 30 appended claims.

In the accompanying drawings:

Figure 1— is a view partly in section showing the U-tube in position for withdrawing the top of the milk from a bottle; 35 also representing the thumb of the operator as closing the valve-opening and simultaneously depressing the bendable disk to create an internal pressure and start the flow outward through the tube.

40 Fig. 2— is a detail of the U-tube representing its two legs as being of different lengths.

Fig. 3— is a perspective view of the disk-shaped bendable stopper showing the tube hole and the valve hole therethrough.

Fig. 4— is an edge view of the stopper disk showing the periphery as beveled which causes it to take a convex shape when positioned in the bottle.

50 Fig. 5— shows the disk as convexed in the neck of the bottle.

My invention comprises primarily a U-shaped tube 10 which is preferably made of glass, the same being bent at 11 to extend

over the upper edge of the bottle neck and 55 providing one short leg 12 to project down into the bottle neck and one longer leg 13 to extend down on the outside of the bottle below the end of the shorter leg. A bendable disk-shaped member 14 which may be made 60 of rubber, leather, celluloid, thin metal or other suitable bendable material, is formed of a size to fit tightly into the neck of a bottle and is provided with a hole 15 near its periphery through which the shorter leg of 65 the tube extends. This disk is also provided with a smaller hole 16 near its center, to serve as a valve as presently described.

It is almost the universal custom in certain sections of the country to deliver milk in 70 glass jars or bottles through which the depth of the separated cream can be readily observed in the neck or top thereof, and it is found quite difficult to pour off this creamy portion without stirring up and taking with 75 it some portion of the thinner milk.

To obviate this difficulty I have provided an extremely simple, practical, effective and sanitary device for withdrawing the exact amount desired from this bottle, to accomplish which it is only necessary to pass the shorter leg of the tube through the hole 15 of the disk, then insert the disk stopper into the neck of the bottle, press the thumb over the valve hole 16 thereby preventing the air 85 from escaping, and then by bending the disk inwardly an air pressure is created within the bottle, which causes the contents to rise in the tube over the bend and run down the longer leg 13 into the receptacle 17. The 90 thumb is now withdrawn from the valve opening permitting the air to enter and the siphonic action in the tube causes all of the cream above the lower end 18 of the tube to run out. The discharge may be arrested at 95 any time by simply placing a finger over the valve opening, which will again continue when the finger is removed. When the contents have been drawn down to the lower end of the tube the liquid will automatically 100 cease to run.

One of the features of this simple device is that the tube may be readily adjusted vertically through the disk stopper so that its lower end may be positioned at the mark of separation between the milk and the cream at whatever height that may be.

Another feature of this invention is that I

bevel the edge 18 of the disk whereby when it is placed in the bottle with its greatest diameter downward it will naturally stand in a convex position, as best illustrated in Fig. 5, so that a slight pressure on its surface will force it from this convex to the concave position as illustrated in Fig. 1, which action is sure to create sufficient pressure within the bottle to force the contents out through the tube.

I have shown and described my improved device as being applied to a milk bottle for withdrawing the top of its contents, but this device may be used for any purpose for which it may be adapted. I have also shown and described the stopper as being set into a groove within the neck of the bottle, but my invention is designed to cover a disk or other form of cap held in any way on the receptacle whereon a depression of the same creates a pressure within the bottle to force its contents outward through the tube. I reserve the privilege of resorting to all the mechanical changes to which the device is susceptible, the invention being defined and

limited only by the terms of the appended claims.

I claim:

1. A siphon device comprising a thin resilient disk having its edge shaped to fit air tight in the internal annular groove in the neck of a milk bottle, said disk being provided with a vent hole near its center and a tube hole near its edge, and a U-tube having one leg adjustably held in said tube hole to extend into the bottle.

2. A siphon device comprising a concavo-convex disk having a thin beveled edge to fit tight in the internal annular recess in the neck of a milk bottle, said disk being provided with a vent hole near its middle portion and a tube hole near its edge, and a U tube having one leg adjustably held in said tube hole to extend into the bottle.

In testimony whereof I affix my signature in presence of a witness.

GEORGE W. LAKE.

Witness:

HOWARD E. BARLOW.
